Starrett, Attn:

UNITED STATES PATENT OFFICE.

HARRY R. COREY, OF BROOKLYN, NEW YORK, ASSIGNOR TO AMERICAN CAN COMPANY, OF NEW YORK, N. Y., A CORPORATION OF NEW JERSEY.

DESIGN FOR A TALCUM-POWDER BOX.

57,033.

Specification for Design.

Patented Feb. 1, 1921.

Application filed March 13, 1919. Serial No. 282,514. Term of patent 14 years.

To all whom it may concern:

Be it known that I, HARRY R. COREY, a citizen of the United States, residing at Brooklyn, in the county of Kings and State of New York, have invented a new, original, and ornamental Design for a Talcum-Powder Box, of which the following is a specification, reference being had to the accompanying drawing, forming a part thereof.

On the drawing:

Figure 1 is a side elevation of a talcum

powder box embodying my present invention; and

Fig. 2 is a top plan view thereof.

I claim:

The ornamental design for a talcum powder box, as shown.

HARRY R. COREY.
